(57) **CLAIM**

The ornamental design for a truck, as shown and described.

DESCRIPTION

FIG. 1 is a front, left perspective view of a truck showing our new design;

FIG. 2 is a rear, right, top perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The broken lines and the deemphasized area contained within the broken lines in FIG. 6 are for the purpose of showing a portion of the truck that does not form a part of the claimed design.

1 Claim, 7 Drawing Sheets
